(57) **CLAIM**

We claim the ornamental design for a stool, as shown and described.

DESCRIPTION

FIG. 1 is a perspective view of a stool, according to a first embodiment.

FIG. 2 is a side view of the stool of FIG. 1.

FIG. 3 is a front view of the stool of FIG. 1.

FIG. 4 is a rear view of the stool of FIG. 1.

FIG. 5 is a top view of the stool of FIG. 1.

FIG. 6 is a perspective view of a stool, according to a second embodiment.

FIG. 7 is a side view of the stool of FIG. 6.

FIG. 8 is a front view of the stool of FIG. 6.

FIG. 9 is a rear view of the stool of FIG. 6; and,

FIG. 10 is a top view of the stool of FIG. 6.

The broken lines shown in the drawings illustrate portions of the stool that form no part of the claimed design.

1 Claim, 8 Drawing Sheets
